UNITED STATES PATENT OFFICE

EDWARD REUKAUF, JR., OF PHILADELPHIA, PENNSYLVANIA, ASSIGNOR TO CAREY-MCFALL CO., OF PHILADELPHIA, PENNSYLVANIA, A CORPORATION OF PENNSYLVANIA

WINDOW SHADE BRACKET

Application filed January 2, 1930. Serial No. 418,051.

This invention relates to brackets for supporting window shades, and especially to the hooded type of bracket employed in automobiles of the closed types.

5 The brackets employed in automobiles usually consist of two parts, one of which comprises a foot provided with screw-holes by which the bracket is secured in place, and extending at right angles from the said foot 10 is a circular portion in which is formed an aperture, either circular or rectangular, which is adapted to receive the spindle of the window shade roller.

In order to conceal the end of the roller 15 spindle these brackets are usually provided with a hood, forming the second part of the bracket, which is of a circular concaved form and is adapted to be located on the outside of the bracket to enclose the end of the roller 20 spindle, the hood being provided with a flange which is turned over the edge of the circular portion of the bracket for holding the hood in place.

Brackets of this two-piece type involve 25 considerable expense in manufacture, as it is necessary to provide separate dies for the bracket proper and the hood which is subsequently applied thereto. Also there are times when these hoods are not rigidly 30 secured to the body of the bracket, which consequently produces a rattle when the automobile to which they are applied is in motion.

The bracket forming the subject of my invention is made in one piece, and thereby obviates any noise due to loose parts vibrating 35 when the car is in motion; it reduces the cost of manufacture to a minimum, and in outward appearance is the same as the two-part hooded type bracket, functioning in the same 40 manner as the two-piece hooded bracket in that the end of the roller spindle is entirely enclosed and concealed.

Referring to the accompanying drawings:

45 Fig. 1 is an elevation of a bracket located at one side of a window shade;

Fig. 2 is a front elevation of the bracket adapted to be located at the opposite side of the curtain;

50 Fig. 3 is a perspective view of a bracket

made in accordance with the principles of my invention;

Fig. 4 is a side elevation of the bracket shown in Fig. 3;

Fig. 5 is a sectional view taken on the line 5-5, Fig. 4;

Fig. 6 is a sectional view taken on the line 6-6, Fig. 4;

Fig. 7 is a view of a bracket in one stage of the process of manufacture; and

Figs. 8 and 9 illustrate a modified form of the invention.

As above noted my improved bracket is made in one piece and comprises a foot-plate 1 having a flange 2 extending substantially around the whole of the foot-plate.

The foot-plate 1 is provided with screw-holes 3, 3, respectively, surrounded by angularly disposed flanges 4, 4, providing countersunk sockets for the heads of the screws by which the bracket is adapted to be secured in place.

Intermediate its ends, along one of the longitudinal edges of the foot-plate 1, the foot-plate is provided with a neck 5, the center line of which extends substantially at right angles to the foot-plate 1. At the outer end of the neck 5 is a circular portion 6 which is provided with a concaved hood section 7. The neck 5 and circular portion 6 of the bracket are provided with a flange 8.

Formed integral with the circular portion 6, or the flange 8 thereof, is a tongue 10 which is adapted to be bent inwardly over, and in a plane substantially parallel to the plane of, the circular portion 6 and the neck 5 of the bracket, the said tongue extending across the center α of the said circular portion 6 and the concaved hood portion 7 thereof.

In the tongue 10 is formed an aperture 11 which may be either rectangular, as illustrated in Figs. 3, 4 and 7, for the reception of the spring-carrying spindle of a window shade, or which may be circular, as illustrated at 12 in Fig. 1, for the reception of the circular trunnion located at the opposite end of a window shade from that occupied by the spring-carrying spindle above noted.

From the drawings, it will be obvious that my improved bracket is stamped in one piece.

from a sheet or strip of metal and flanged in the manner illustrated in Fig. 7, after which the foot-plate 1 is bent into a plane disposed at right angles to the plane of the neck 5, and the tongue 10 bent from the position illustrated in Fig. 7 to that illustrated in Figs. 3 and 4, and wherein the tongue 10 is shown as lying flat against the circular portion 6 and within the confines of the flange 8 thereof, thereby completing the bracket.

In Figs. 8 and 9 I have illustrated a modified form of the invention wherein the neck 5a is elongated and the circular portion 6a with the hood 7a formed therein is bent inwardly over and against the neck 5a, the spindle aperture being formed in the said neck 5a, which functions in the same capacity as the tongue 10.

I claim:

1. A one-piece hooded bracket, for supporting the roller of a window shade and the like, comprising a single sheet metal stamping consisting of an element provided with an aperture adapted to receive a projection on the end of the roller, and an imperforate cover element formed integral with the apertured element and extending over the aperture at one side of the apertured element.

2. A one-piece hooded bracket, for supporting the roller of a window shade and the like, comprising a single sheet metal stamping consisting of an element provided with an aperture adapted to receive a projection on the end of the roller, and an imperforate cover element formed integral with the apertured element and extending over the aperture at one side of the apertured element, said cover element being concaved in line with the aperture to accommodate and conceal a projection on the end of the roller which is adapted to extend through the aperture.

3. A one-piece hooded bracket, for supporting the roller of a window shade and the like, comprising a single sheet metal stamping consisting of a body portion including an imperforate cover portion, and a tongue formed integral with and extending inwardly from the edge and across the center of said imperforate cover portion, said tongue having an aperture adapted to receive a projection on the end of the roller.

4. A one-piece hooded bracket, for supporting the roller of a window shade and the like, comprising a single sheet metal stamping consisting of a body portion, and a tongue formed integral with and extending inwardly from the edge of said body portion, said tongue having an aperture adapted to receive a projection on the end of the roller, said body portion being concaved and imperforate in line with said aperture to accommodate and conceal the end of the projection extending through the aperture.

5. A one-piece hooded bracket, for supporting the roller of a window shade and the

like, comprising a single sheet metal stamping consisting of a body portion, a tongue formed integral with and extending inwardly from the edge of said body portion, said tongue having an aperture adapted to receive a projection on the end of the roller, said body portion being concaved and imperforate in line with said aperture to accommodate and conceal the end of the projection extending through the aperture, and a foot formed integral with said body portion and provided with an opening adapted to receive an element by which the bracket may be secured to a supporting structure.
